UNITED STATES PATENT OFFICE.

ALBERT W. PEARSALL, OF LOWELL, MASSACHUSETTS, ASSIGNOR TO THE LAMSON COMPANY, (FORMERLY LAMSON CONSOLIDATED STORE SERVICE COMPANY,) OF BOSTON, MASSACHUSETTS, A CORPORATION OF NEW JERSEY.

PNEUMATIC-DESPATCH-TUBE APPARATUS.

1,208,195.

Specification of Letters Patent. Patented Dec. 12, 1916.

Application filed September 16, 1912. Serial No. 720,560.

To all whom it may concern:

Be it known that I, ALBERT W. PEARSALL, of Lowell, in the county of Middlesex and State of Massachusetts, have invented certain new and useful Improvements in Pneumatic-Despatch-Tube Apparatus, of which the following is a specification.

This invention relates to improvements in pneumatic despatch tube apparatus, and particularly to those systems which comprise a single transmission tube through which a carrier can be despatched in either direction.

The object of this invention is to pneumatically control the power from either terminal of said tube in such a manner as to cause the blower or pump which is connected with one end of the tube to supply a current of air in the proper direction for the transmission of the carrier. This is accomplished by means of a pneumatically operated switch controlled from either end of the transmission tube and adapted to reverse the direction of rotation of the motor and therefore of the blower or pump and necessarily changing the direction of the current of air in the transmission tube.

Another object of this invention is to automatically regulate and limit the operation of the blower or pump to the interval necessary to the proper transmission and delivery of the carriers.

Other important features of this invention will be hereinafter described and particularly pointed out in the claims.

In the accompanying drawings which illustrate a construction embodying my invention, Figure 1 is a diagrammatic view of the device in operating connection with a single tube pneumatic despatch system. Fig. 2 is an enlarged front elevation of the automatic motor reversing switch hereinafter described. Fig. 3 is an inverted plan view of the switch shown in Fig. 2. Fig. 4 is an enlarged view of the automatic timing mechanism. Figs. 5 and 6 are enlarged details hereinafter described.

Like letters of reference refer to like parts throughout the several views.

A and B represent two stations connected by a transmission tube C normally open to the atmosphere at station A and closed at the opposite end at station B by a lock valve C'. An elbow c' connects the end of the

transmission tube at station B with the 55 blower or pump I by means of the tube c'. The blower I is driven by means of the belt 2 by electric motor 3; this motor 3 is series-wound and its circuit includes a normally open reversing switch 4 by means of which 60 the motor may be started in either direction and stopped.

D is an ordinary cut out switch connecting the motor circuit with line wires L' and L². 65

As shown in Figs. 2 and 3, the switch 4 comprises a plate or slate 5 to which is fixed a casing 6 containing a diaphragm 7 which normally maintains an intermediate position. To this diaphragm 7 is fixed a stem 8 70 movable vertically through the casing 6; at its upper end, the stem 8 is provided with a collar 9 adapted to coöperate with a yoke 10 pivoted at 10^a to an extension 6^a of the casing 6, and at its lower end said stem is connected by a pin 11 with the slotted arms of two bell-crank levers 12, 13 pivotally mounted at 14 and 15 upon the slate 5. The longer arms of the bell cranks 12 and 13 carry, respectively, contacts 16 and 17, and 80 are offset relatively, as shown in Fig. 3, so that when the stem 8 is lifted, said arms can pass each other as indicated by dotted lines Fig. 2. Mounted on the slate 5 in position to coöperate with the contacts 16 85 and 17 are two stationary contacts 18 and 19 against which one or the other of the contacts 16 and 17 is brought when the stem 8 is raised or lowered, that is, the stem 8 is held by the diaphragm 7 normally in an 90 intermediate position whereby to position each of the parts 12 and 13 substantially in its median or inoperative position, in which these parts are shown in Fig. 2, and when said stem is raised, the bell cranks 12 and 13 95 are swung past each other into the dotted line positions shown in Fig. 2, thus connecting the bell crank 12 with the contact 19 and bell crank 13 with the contact 18, and when said stem is lowered, bell cranks 12 and 13 100 swing apart, thus connecting the bell crank 12 with the contact 18 and the bell crank 13 with the contact 19. To counterbalance the horizontal slotted short arm of the bell cranks, the latter are weighted as at 20 105 and 21.

Connected with the casing 6 at a point above the diaphragm 7 is a pipe 22 which

extends to the station A and is provided at that end with a compressible bulb 23, and as will be clear, when this bulb is compressed by the operator at station A, air is forced into the casing 6 above the diaphragm 7 and the latter, together with the stem 8 is forced down into the lower dotted position (Fig. 2) so that the bell cranks 12 and 13 connect with the contacts 18 and 19 respectively. This results in the motor I being started in a direction to produce a current of air from station A to station B so that if a carrier be then inserted at station A it will be propelled to station B.

15 Inasmuch as the motor I remains in operation only so long as contacts 16 and 17 are against 18 and 19, and since it is not desirable to depend upon the operator at station A holding the bulb 23 compressed until

20 the carrier is delivered at station B, I utilize the relatively low pressure in front of the carrier while traveling from station A to station B to hold the contacts 16 and 17 against contacts 18 and 19; to this end, a

25 pipe 24 is provided which connects the casing 6 at a point below the diaphragm 7 with the tube C at a point just above the valve c^2 , so that after the carrier is inserted in the tube C at station A, and until it is discharged at station B, the relatively low pressure or vacuum in the tube C in front of the carrier acts through the pipe 24 to exhaust air from the lower part of casing 6 thereby holding the diaphragm 7 down un-

30 til the carrier discharges at station B through the valve c^2 , which is accomplished by the carrier tripping the latch c^4 and releasing the valve c^2 . As soon as the carrier passes the junction of pipe 24 and tube C, 35 the pressure in the lower part of the casing 6 is restored to normal and the diaphragm 7 returns to its normal intermediate position, disconnecting the contacts 16 and 17, and 18 and 19, thereby stopping the motor I.

40 In sending a carrier from station B to station A, the operator at station B opens the valve c^2 and inserts the carrier into the tube C, closing and locking the valve c^2 , then, by means of the yoke lever 10, raises the stem 8, thereby swinging bell cranks 12 and 13 past each other into the crossed dotted line positions indicated in Fig. 2, which connects the bell crank 12 with the contact 19, and the bell crank 13 with the contact 18, and results in motor I being started in the opposite direction, that is, so as to establish a current of air and propel the carrier from station B to station A.

45 In sending a carrier from station B to station A, it is not desirable to depend upon the operator at B holding the stem 8 elevated until the carrier despatched at B is delivered at A, and for this reason, the relatively high pressure in the tube C behind the carrier is utilized for this purpose.

The pipe 24 being open when a carrier is despatched from station B to station A permits air to flow from the tube C into the lower part of chamber 6, thereby holding the stem 8 elevated until the carrier is delivered at station A. When this happens, the high pressure below the diaphragm 7 is automatically relieved as hereinafter described, and the diaphragm 7 assumes its normal intermediate position breaking the circuit of 70 motor I at 16-17, and 18-19. Mounted in the pipe 24 is a three-way valve 25 of which one of its ports 26 opens to the atmosphere; normally this valve 25 occupies the position shown in Fig. 5 with the port 26 closed and 75 chamber 25^a in communication with the tube C through the pipe 24. When, however, a carrier traveling from station B to station A discharges at station A, the valve 25 is automatically shifted by means of timing 80 mechanism into the position indicated by dotted lines in Fig. 5, thereby closing that section of pipe 24 leading to the tube C and opening to the atmosphere that section of pipe 24 which leads to casing 6. This results in the stopping of the motor I after 85 the carrier has delivered at station A.

In order to operate valve 25 automatically and at the proper time, there is provided a timing device comprising the cylinder 27 connected at its lower end by a port 28 with the tube C. At its upper end the cylinder 27 carries a relatively large port 29 controlled by an outwardly closing check valve 30, Fig. 6. Through the valve 30 extends a 90 restricted by-pass 31 whose capacity is regulated by a screw valve 32; within the cylinder 27 is a piston 33 whose stem 34 is made at its upper end with a slot 35 into which extends an arm 36 fast to the stem 37 of the valve 25. Normally the piston 33 rests at the bottom of the cylinder 27, but when the motor I is started to propel a carrier from station B to station A, the pressure below the piston raises the latter against the resistance 95 offered by the restricted by-pass 31 which is so regulated that when a carrier discharges at station A and motor I should be stopped as described, the lower end of slot 35 engages the arm 36 and valve 25 is shifted from its full line position to its dotted line position, Fig. 5, which, as already described, results in stopping the motor I. As soon as the motor I stops, the pressure below the piston 33 falls and the weight of the latter causes it 100 to descend, the check valve 30 opening to permit the free entrance of air, as the piston moves downward. The port 29 however, is of such capacity that the motor I is stopped before the upper end of slot 35 engages the arm 36 and restores the valve 25 to its normal position. When closed by the operator at station A, the stem 8 then being forced down by means of bulb 23, the circuit of 105 motor I is as follows: from line wire L' 110

through a wire 38 to bell crank 12 and contact 16, thence to contact 18, from which a wire 38 leads to one brush of motor I; through armature of motor I to the other 5 brush which is connected by wire 40 with contact 19, thence through contact 17 and bell crank 13 to a wire 41 to the field of motor I; through field of motor I to wire 42 which connects with the other line L².
 10 When closed by the operator at station B, the stem S being then forced up, the circuit of motor I is as follows: from line wire L' through wire 38 to bell crank 12 and contact 16 thence through contact 19 and wire 40 15 to one of the brushes of armature of motor I, through the armature to the other brush thence through wire 39 to contact 18, thence through contact 17, bell crank 13 and wire 41 to the field of motor I and through the 20 field to wire 42 which connects with line wire L². It will thus be seen that when stem 8 is raised from normal position, the current through the armature of motor I is in one direction, and when said stem 8 is depressed, 25 the current through the armature is in the opposite direction, while the direction of the current through the field is always the same; thus when the stem 8 is raised by the operator at station B, the motor I will operate in one direction, and when said stem 8 is lowered by the operator at station A, the motor 30 I will operate in the opposite direction.

I do not limit myself to the arrangement and construction shown, as it may be varied 35 without departing from the spirit of my invention.

Having thus described the nature of my invention and set forth a construction embodying the same, what I claim as new and 40 desire to secure by Letters Patent of the United States is:

1. In a pneumatic despatch tube apparatus, a transit tube for the transmission of carriers in either direction, a pump connected with said tube and adapted to supply a current of air in either direction through said tube for the transmission of carriers, a motor adapted to drive said pump, a switching device for starting, stopping or reversing said motor, and pneumatically controlled means, subject in part at least to the pressure in a portion of said tube, for operating said switching device to stop said motor.

2. In a pneumatic despatch tube apparatus, a transit tube for the transmission of carriers in either direction, a pump connected with said tube and adapted to be reversed for supplying a current of air in either direction through said tube for the 55 transmission of carriers, a motor adapted to drive said pump, a switching device having a part thereof movable in either of two directions away from a median position, said device being adapted to start, stop or 60 reverse said motor, and time element means 65

for controlling a motor stopping operation of said switching device, said device having a tendency for its median position.

3. In pneumatic despatch apparatus, a tube, means for establishing a carrier-transmitting flow of air through said tube in either direction, and mechanism for controlling the duration of running of said means, when the latter is in operation, by either vacuum or plenum in a part of said tube, according to the direction of said flow.

4. In a pneumatic despatch tube apparatus, a transit tube for the transmission of carriers in either direction, a pump connected with said tube and adapted to be reversed for supplying a current of air in either direction through said tube for the transmission of carriers, a motor adapted to drive said pump, a switch adapted to start, stop or reverse said motor, means for timing the operation of said motor in one direction, and pressure controlled means adapted to co-act with said switch to stop the actuation of said motor when the latter is running in the opposite direction.

5. In a pneumatic despatch tube apparatus, a transit tube for the transmission of carriers in either direction, a pump connected with said tube and adapted to be reversed for supplying a current of air in either direction through said tube for the transmission of carriers, a motor adapted to drive said pump, a switch adapted to start, stop or reverse said motor, means for controlling the operation of said switch for starting or reversing said motor and for automatically stopping said motor when it is being driven in one direction, upon the establishment of a determined carrier transmitting condition in a part of the system, and means for timing the duration of operation of said motor when being driven in the opposite direction.

6. In pneumatic despatch apparatus, a transmission tube, means for establishing a carrier propelling current of air through said tube, and means for limiting the duration of said current to a determined period of time, said last mentioned means including a conduit in communication with said tube, a normally open valve in said conduit, means, subject to the pressure in said conduit, for controlling said first mentioned means, and time element mechanism for controlling said valve whereby to vary said pressure in said conduit.

7. In pneumatic despatch apparatus, a transmission tube, means for establishing a carrier propelling current of air through said tube, and means for limiting the duration of said current to a determined period of time, said last mentioned means including a conduit in communication with said tube, a valve in said conduit and adapted to obstruct the same when in its closed position,

means, subject to the pressure in said conduit for controlling said first mentioned means, and time element mechanism for actuating said valve after the lapse of substantially said determined period of time.

8. In pneumatic despatch apparatus, a transmission tube, means including a reversible motor for establishing a carrier propelling current of air through said tube in either direction, and pneumatic timing means for automatically limiting the duration of said current to a substantially determined period of time when said motor is driven in one direction, said timing means being substantially inoperative when said motor is being driven in the opposite direction, and means for stopping said motor when it is being driven in said opposite direction, after the transmission of a carrier by said current through said tube to a determined point.

9. In pneumatic despatch apparatus, a transmission tube, means including a reversible motor for establishing a carrier propelling current of air through said tube in either direction, and timing means for automatically limiting the duration of said current to a substantially determined period of time when said motor is driven in one direction, said timing means being substantially inoperative when said motor is being driven in the opposite direction, and means for stopping said motor when it is being driven in said opposite direction, after the transmission of a carrier by said current through said tube to a determined point.

10. In pneumatic despatch apparatus, operating mechanism for said apparatus, enclosed in a casing, a transmission tube adapted for the transmission of carriers in either direction therethrough, said tube extending from said casing, said mechanism including a blower or pump, a reversible motor for driving the latter, a switching device for said motor, normally in a motor stopping position and means for actuating said device to drive said motor in one direction, said means being operable from a point adjacent said casing, means to actuate said device for driving said motor in an opposite direction, operable from a point at substantially the other end of said tube, and

means to co-act with one of said switching device actuating means to return the latter to its motor stopping position independently of the travel of the carriers.

11. In a pneumatic despatch apparatus, a transmission tube, means, including a motor, reversible for establishing a current of air in said tube in either direction, a switching device for controlling said motor, and means adapted to be held in one of two positions to maintain parts of said switching device in operative relationship, by the pressure of the air flowing through said tube and in accordance with the direction of flow of said air.

12. In a pneumatic despatch apparatus, a transmission tube, means, including a motor, reversible for establishing a current of air in said tube in either direction, a switching device for controlling said motor, and means to maintain parts of said switching device in operative relationship, by the pressure of the air flowing through said tube and in accordance with the direction of flow of said air.

13. In a pneumatic despatch apparatus a transit tube for the transmission of carriers in either direction, a blower or pump connected with said tube and adapted to be reversed for supplying a current of air in either direction through said tube for the transmission of carriers, a motor adapted to drive said blower or pump, a switch adapted to start, stop or reverse said motor, means for controlling the operation of said switch for starting or reversing said motor and for automatically stopping said motor when it is being driven in one direction, upon the establishment of a determined pressure in a part of the system, and means, co-acting with certain of the elements aforesaid, for controlling the duration of operation of said motor when being driven in an opposite direction.

In testimony whereof, I have signed my name to this specification in the presence of two subscribing witnesses.

ALBERT W. PEARSALL.
